UNITED STATES PATENT OFFICE.

ALBERT E. JOHNSON, OF BROCKTON, MASSACHUSETTS, ASSIGNOR TO
UNITED SHOE MACHINERY COMPANY, OF PATERSON, NEW JERSEY,
A CORPORATION OF NEW JERSEY.

INSOLE FOR USE IN THE MANUFACTURE OF BOOTS AND SHOES.

No. 849,245.

Specification of Letters Patent.

Patented April 2, 1907.

Application filed July 14, 1903. Serial No. 165,477.

To all whom it may concern:

Be it known that I, ALBERT E. JOHNSON, a citizen of the United States, residing at Brockton, in the county of Plymouth and State of Massachusetts, have invented certain new and useful Improvements in Insoles for Use in the Manufacture of Boots and Shoes; and I do hereby declare the following to be a full, clear, and exact description of the invention, such as will enable others skilled in the art to which it appertains to make and use the same.

The present invention relates to an improvement in insoles for use in the manufacture of boots and shoes, and more particularly for use in the manufacture of welt boots and shoes.

The object of the present invention is to produce a reinforced lipped insole strong in construction and cheaper than prior insoles of which the applicant is aware.

To the above end the present invention consists in the improved insole hereinafter described, and particularly defined in the claims.

In the accompanying drawings, illustrating the preferred form of the invention, Figure 1 is a plan of the improved insole; and Figs. 2, 3, 4, and 5 illustrate the method of making the improved insole, Fig. 5 being a cross-section, enlarged, on the line $z-z$, Fig. 1.

The preferred embodiment of the present invention illustrated in the drawings consists of a body portion 1, made of leather and cut to the desired shape of the insole. Fig. 2 illustrates in section the blank for the body portion of the insole. This blank is split, as shown in Fig. 3, on the line 2 around the shank and fore part to form a lip 3 and feather 4. A channel 5, as shown in Fig. 3, is also cut around the shank and fore part of this blank, thereby forming a second lip 6 alongside of the lip 3, above referred to. These two lips 3 and 6 are preferably cut simultaneously and turned up at right angles to the body portion of the insole and united together by cement and pressure to form a single practically integral lip around the shank and fore part of the body portion of the insole, as shown in Fig. 4. A reinforcing-cover 7 is cemented to the body portion, preferably within the lip and to the inside or inner face of the lip, as shown in Fig. 5.

The reinforcing-cover 7 in the illustrated embodiment of the invention covers the entire innersurface of the lip and the entire central part of the body portion of the insole—that is, that part of the body portion of the insole inclosed by the lip. The material of the body portion is preferably made of leather, although it is within the purview of the invention to use other material in its stead. The material for the reinforcing-covering is, in the illustrated embodiment of the invention, a heavy cotton duck or canvas; but any suitable strengthening material may be employed at the choice of the constructor.

It will be observed that the channel cutting the second lip from the insole forms a groove inside of the lip, which reduces the thickness of the insole at this place approximately to the thickness of the feather of the insole. This is a feature of advantage accruing from the preferred construction, because in the welt-sewing machines usually employed for sewing the inseam, which unites the insole, upper, and welt, the curved needle enters from the outside and should emerge at the base of the inside of the lip, and it is apparent that when the feather is thinner than the insole inside of the lip the needle is liable to penetrate the body portion of the insole beyond the lip, thereby impairing the product by the weakening of the seam.

It is preferred to unite the two lips 3 and 6 by means of a cement, although other means of uniting the two lips to form a practically integral lip may be employed, if desired. It is also preferred to secure the reinforcing-cover to the body portion by means of cement, but other means of efficiently securing the cover to the body portion may be employed, if preferred. It is also preferred that the reinforcing-cover be secured to the inner face of the lip and to the body portion of the insole within the lip, although the invention in its broader aspect contemplates securing the reinforcing-cover to either the inner or the outer face of the lip and to the adjacent part of the body portion, so that the angle between the lip and body portion is covered by the reinforcing material.

It will be observed that the present construction permits the use of relatively thin material for the body portion of the insole, for the lips cut from the body portion may

each be thin and still together produce a single lip, which taken with the reinforcing material will be of such thickness and strength as to afford ample material to receive and hold the stitches of the inseam and to produce a strong and durable shoe. The saving effected by the use of thinner or poorer stock for the body portion of the insole is considerable and affords a material economy in manufacture.

Having thus described the invention, what is claimed is—

1. An insole for use in manufacturing sewed shoes, consisting of a body portion having two lips cut therefrom, turned up and permanently united throughout their length to form a single stitch-receiving lip.
2. An insole for use in manufacturing sewed shoes, consisting of a body portion having two lips cut therefrom, and turned up

and united together by cement and pressure to form a single compressed stitch-receiving lip around the shank and fore part of the body portion of the insole.

3. An insole for use in manufacturing sewed shoes, consisting of a body portion having two lips cut therefrom and turned up and united to form a single stitch-receiving lip around the shank and fore part of the body portion of the insole, and a sheet of reinforcing material cemented to the surface of the body portion and to the inner surface of the lip.

In testimony whereof I affix my signature in presence of two witnesses.

ALBERT E. JOHNSON.
